UNITED STATES PATENT OFFICE.

EDSON C. COVERT, OF NEW KENSINGTON, PENNSYLVANIA, ASSIGNOR TO HEYL & PATTERSON, INC., OF PITTSBURGH, PENNSYLVANIA, A CORPORATION OF PENNSYLVANIA.

FEEDER FOR PULVERULENT FUEL.

1,197,799.

Specification of Letters Patent. Patented Sept. 12, 1916.

Application filed October 28, 1915. Serial No. 58,413.

To all whom it may concern:

Be it known that I, Edson C. Covert, a citizen of the United States, and resident of New Kensington, in the county of Westmoreland and State of Pennsylvania, have invented a new and useful Improvement in Feeders for Pulverulent Fuel; and I do hereby declare the following to be a full, clear, and exact description thereof.

10 My invention relates to a feeder for pulverulent or finely divided fuel, such as coal. The most efficient feeder for pulverized coal is one that is always under perfect control, and for this reason devices of this character have come to be known as "controllers". The difficulties most commonly encountered in the use of these controllers are, lack of uniformity of feed, and a tendency of the coal to continue to flow after the controller has stopped. This tendency to flow, which is sometimes called "flooding", is due to the very small angle of repose of dry pulverized coal, and this is accentuated, the drier and more finely pulverized the coal. 20 Nearly all the mechanical controllers of this character employ some form of screw as a means of feeding, but on account of "flooding" the amount delivered to the burner is subject to considerable fluctuation and the 30 stoppage of the flow of coal when the screw stops is by no means assured. Furthermore, where air is used for feeding the coal from the controller to the burner, the amount of pressure has considerable influence on the 35 quantity of coal that is delivered.

The object of my invention is to provide a controller or feeder of such character that the coal will be delivered in practically uniform quantities, and one which when the 40 feeder is at rest, shuts off the supply of coal completely and prevents "flooding" heretofore referred to.

To these ends, my invention consists, generally stated, in combining two screw-feeders in such a way that neither can feed independently of the other and that when at rest, each seals the other against the passage of any material. This is accomplished by mounting two screws of similar size and 50 pitch and of the same hand with their axes at such an angle to each other that a line on the surface of one thread of one screw is in approximate contact with a line on the surface of the space on the other screw. 55 This line of contact being common to both

screws, it is evident that the thread of one screw effectually fills the space of the other. Thus the free flow of material along either screw is prevented.

In the accompanying drawings, Figure 1 is a plan view partly broken away, of my improved feeder or controller; Fig. 2 is a side view partly broken away; and Fig. 3 is a section on the line 3—3, Fig. 1.

In the drawing, the numeral 2 designates a suitable housing or casing having the material-receiving chamber 3, the discharge opening 4, and two cylindrical intersecting passages 5 connecting the receiving-chamber with the discharge opening. The intersecting passages communicate at their point of intersection as at 5^a. Mounted in the passages 5 are the feed-screws 6 and 7, said feed-screws engaging where said passages intersect, and being arranged with their axes at such an angle to each other that a line on the surface of one thread of one screw is in approximate contact with a line on the surface of one space of the other screw. This line of contact being common to both screws, it is evident that the thread of one screw effectually fills the space of the other, and thus the free flow of material along either screw is prevented. The 70 screws are provided with the pinions 8 driven by the intermediate pinion 9, so that the screws rotate in the same direction. As both screws are restrained from endwise motion, it is evident that neither may turn unless the other turns at the same time in the 75 same direction. In their rotation, the screws present successively new surfaces to each other, but in each position that they assume, these surfaces have a common line of contact where they are meshed together. Since 80 the obstruction which the thread of each screw presents to the passage of material along the space of the other is not fixed, but moves as the screws rotate, it is evident that there is no sealing of the passages except against the movement of material at a 85 faster rate of travel than would be produced by the rotation of the screws. There is thus obtained a uniform feed proportionate to the rate of movement of the screws and absolute stopping of the feed while the screws are at rest. In this manner, "flooding" is 90 prevented, and the uniformity of feed is obtained by reason of the fact that there is 95 no flow of fuel except as it is advanced by 100 105 110

the screws, and when the screws stop, the flow of fuel absolutely ceases.

What I claim is:

- 5 1. In a feeder or controller for pulverulent fuel, the combination with a suitable casing, an inlet opening, a discharge opening, two feed screws located in said housing adapted to rotate in the same direction and having their threads in engagement throughout a portion only of the length of the screws to seal the discharge opening.
- 10 2. In a feeder or controller for pulverulent fuel, the combination of a suitable casing, having an inlet and discharge opening; two screws located in said casing with their axes at an angle to each other adapted to rotate in the same direction, and having threads in engagement with each other.
- 15 3. In a feeder or controller for pulverulent fuel, the combination of a suitable casing, having an inlet and discharge opening; two screws located in said casing with their axes at an angle to each other, adapted to rotate in the same direction, and having their threads of the same hand and in engagement with each other at a point between said inlet and discharge opening and permanently closing communication between said openings.
- 20 4. In a feeder or controller for pulverulent fuel, the combination of a suitable casing, having inlet and discharge openings, a conveyer chamber interposed between said openings and provided with two horizontal fuel delivery passages, two conveyer screws located in said passages with their axes at an angle to each other, and their threads in full engagement at a point in said passages.
- 25 5. In a feeder or controller for pulverulent fuel, the combination of a suitable casing, having an inlet and discharge opening; two screws located in said casing with their axes at an angle to each other adapted to rotate in the same direction and having their threads in engagement throughout a portion only of the length of the screws to seal the discharge opening.

lent fuel, the combination of a suitable casing, having inlet and outlet openings, a conveyer chamber having two fuel delivery passages connecting the inlet and discharge and crossing each other, said passages communicating at the point of intersection, two conveyer screws in said passages having their threads engaging at the point of intersection of said passages, and means for driving said screws in the same direction.

45

50

6. In a feeder or controller for pulverulent fuel, the combination of a suitable casing, having inlet and discharge openings, a conveyer chamber interposed between said inlet and discharge and provided with two delivery passages at an angle to each other and intersecting at a point intermediate said inlet and discharge, two conveyer screws in said passages with their screws in engagement at the intersection of said passages, and means for rotating said screws in the same direction.

55

7. In a feeder or controller for pulverulent fuel, the combination of a suitable casing, having inlet and discharge openings, and a conveyer chamber interposed between said openings, said conveyer chamber having intersecting conveyer passages communicating with the said inlet and discharge openings, and conveyer screws in said passages with screws of like hand and in engagement with each other at the intersecting point of the screws at the intersection of said passages.

60

In testimony whereof, I, the said EDSON C. COVERT, have hereunto set my hand.

EDSON C. COVERT.
